[57]

ABSTRACT

A psychological test taking apparatus having its own source of energy, independent of electrical outlets and the like. A series of questions on a paper roll in the machine sequentially appear in a window large enough for the testee to provide an answer beneath the question. Means is provided for actuation by the testee to open the window and to effect actuation of a timing mechanism. Expiry of a given time period prior to the completion of the answer automatically closes the window and marks the expired time on the paper and there is means responsive to actuation by the testee for closing the window and marking the paper if the answer is completed prior to the expiry of the time.

FIG. 17

TESTING MACHINE

This invention relates to psychological testing apparatus referred to as a Jung testing device. Such apparatus may be of the question-answer, sentence-drawing or other related types.

The invention provides important improvements in the art over earlier devices as exemplified in U.S. Pat. Nos. 2,715,784 of Aug. 23rd, 1955 and 2,915,833 of Dec. 8th, 1959. These patents dealt with test taking apparatus comprising structures that included prepared questions, and paper for written answers to the same, a window revealing the question and the paper and a shutter or blind for closing the window. These devices had several inherent shortcomings however, such as continually moving paper, no means of automatically timing the testee, slowly moving shutters, and others. These faults resulted in an inability to precisely time the testee during the answer period.

One basic feature of the present invention is to provide a test taking device which will indicate the ability of a testee in answering one or a series of questions at a preselected time for each question. The apparatus in one aspect is automatic in simultaneous and sequential operations but in another aspect the testee does have overriding manual control under certain circumstances especially with respect to the answering period.

Another important feature of the present invention is the provision of an integral energy source or storing mechanism so that the device can be operated without depending on electrical outlets. This is important if a plurality of testing machines are being used, in classroom environment for example.

Another important feature of the invention is to provide a psychological testing apparatus in which means would be provided to automatically mark the responsive answer material, indicating the elapsed time taken by the testee to answer the given question. Other important improvements and features will be made known from the following description.

From the operational standpoint of this invention, the testee is verbally given the time, i.e., number of seconds, allowed for a question or series of questions which will subsequently appear in a window of the apparatus. The allotted answer period is preset on a timing mechanism on the apparatus by a supervisor. When the testee is ready to begin, he operates a main actuating lever which loads the energy store and then actuates a start/override control which opens a shutter to reveal a question printed on a portion of the writing paper at the top of a writing or window space. Simultaneously, the preset timing mechanism is "wound" to a counting position as the testee begins to write the answer to the question. If the testee should complete his answer before the time limit which has been preset, he may then manually halt the machine by the start/override control which simultaneously actuates means to measure the answer period within the preselected time and which marks the time of the answer period on the question sheet. In so doing, the testee also closes the shutter. However, if the testee should fail to complete the answer within the preset time, the shutter will automatically close to terminate the preselected time for the answer, the timing mechanism marking the paper accordingly. In either case, the answer paper is automatically delivered from the apparatus.

The testee may begin another question by again operating the main actuating lever and start/override control.

According to the present invention therefore a psychological testing apparatus of the question-answer type comprises a casing with a writing window opening therein; a supply of writing paper within the casing and which is uni-directionally movable across the window opening of the casing. A shutter member is provided for effectively opening and closing the window thereby to reveal and cover the writing paper and there is means operable by a testee for preselecting the time during which the window remains open and uncovered by the shutter. Additionally, there is means for automatically operating the shutter to close the window at the termination of the preselected time.

The invention will be more readily understood with reference to the accompanying drawings wherein an embodi-

ment of the invention is illustrated by way of example and in which:

FIG. 1 is a perspective three-quarter view of the test taking apparatus with its cover in place ready for operation;

FIG. 2 is a plan view of the apparatus with the cover removed;

FIG. 3 is a side view of FIG. 2, showing in elevation the energy store subassembly;

FIG. 4 is a partial cross section of the apparatus with the cover in place and showing the paper guide and relative location of the paper marking device;

FIG. 5 is an elevation view, partly in cross section, of the paper drive sprocket shaft and shutter drive pulleys;

FIG. 6 is a detail plan view of the drive subassembly for the paper drive sprocket shaft with interlock, shown in the lower right corner of FIG. 2;

FIG. 7 is a side elevation of the mechanism in FIG. 6;

FIG. 8 is a cross-sectional view of the shutter and guide therefor;

FIG. 9 illustrates the shutter clutch subassembly and a portion of its actuating means;

FIG. 10 shows an end view of the shutter clutch and the energy store release mechanism;

FIG. 11 shows the timing mechanism subassembly located at left-central in FIG. 2;

FIG. 12 shows the manual overriding member;

FIG. 13 shows the paper marking mechanism in side view;

FIG. 14 illustrates in plan view the timing mechanism as well as the switching interlock mechanism interconnecting the timing, paper drive and override subassemblies;

FIG. 15 illustrates in plan view the interlock connections only for the subassemblies in FIG. 14;

FIG. 16 is a plan view of the marker tape assembly; and

FIG. 17 is an elevational view of the escapement mechanism included in the timing section shown in plan view in FIG. 11.

GENERAL LAY-OUT AND OPERATION, FIGS. 1, 2 AND

4

Referring to FIG. 1, the testing apparatus is generally indicated at 1 and includes a cover or casing 2 having a writing window opening 3 displaying a section of writing paper 4, this section including a typed on question 5 and additional space 45 for the testee to write an answer to that question. A shutter 6 is positioned to cover or uncover the writing window 3 and the paper 4, the initial uncovering being effected by actuation of a start/override control, hereinafter referred to as the control 10. The covering of the writing paper 4 will be effected automatically if the testee does not answer the question 5 within a prescribed preset time, the indication thereof being provided by a time indicator 8 movably positioned over a scale 9 on the cover 2. However, if the testee should answer the question before the termination of the prescribed preset time, he may depress the control 10 and this will (a) operate the shutter 6 to a closed position, (b) effect marking of the elapsed time for the answer onto the paper and (c) eject the paper, with answer from the apparatus. A main actuating lever 7 is used to load mechanism to power the device. It will be appreciated that the prescribed preset time for answering the question can be seconds or minutes, depending upon the subject being covered.

Referring to FIG. 2 rotary actuation of lever 7, from its illustrated inoperative position, loads a spring-powered energy store subassembly indicated generally at 12 and renders operable a paper drive axis 16 by unlocking an interlock assembly 18. It will be noted that paper drive axis 16 is interconnected to a paper drive sprocket shaft 14 by way of a bead chain 20 and is interconnected to the interlock assembly 18 through a gear mechanism 22, 24. Further a gear train 74-78 and power shaft 80 from the energy store 12 "winds" the apparatus timing mechanism to a start position, shown generally at 26. FIGS. 9 and 10 show the shutter pulleys and clutches in detail, the shutter being opened by control 10.

The writing paper is drawn from a storage roll 30, FIGS. 2 and 4. The path of travel of the paper is shown in FIG. 4 and illustrates an integral guideway 32 of a pair thereof, one on either side of the cover 2. It will be seen that the paper is drawn downwardly along the bottom of the apparatus to the beginning of the guideways 32 where it is brought around the end of the apparatus remote from the paper roll 30 and then upwardly towards the upper surface of the cover 2 where it passes below the window 3 and then outwardly from the apparatus through a provided slot 34.

ENERGY STORE

As shown in FIGS. 2 and 3, power to operate the apparatus is employed in a spring loaded energy store system 12. The actuating lever 7 is interconnected to a lay shaft 36 mounted on the apparatus base, the end of the shaft 36 remote from the actuating lever 7 having a crank 38 secured thereto. Crank 38 is connected via a swivel 40 to a first cable 42 which is trained around idler pulleys 44 and 46 and then around a first or small sheave 48 of a pair thereof mounted on a lay shaft 50. The terminating end of the cable 42 is connected to one end of a first spring 52 (relaxed position shown), the other end of this spring being removably secured to a stationary hook 54 secured to the base of the apparatus. It will be noted from FIGS. 2 and 3 that sheave 48 is rotated by movement of the cable 42 through its connection to the sheave 48 by way of an anchoring screw 56.

Sheave 48 is interconnected to a second or large sheave 58 (coaxially mounted on shaft 50) by means of a screw 60 anchored in the sheave 48 but being rotationally free within the sheave 58 through the provision of an arcuate slot 62 as shown in FIG. 3. Sheave 58 also anchors one end of a second cable 64 by means of a securing screw 66 (FIG. 3), this cable 64 being positioned in a groove 68 of the sheave and terminating in a connection to one end of a second spring 70, the other end of spring 70 being hooked onto an anchor pin 72 (FIG. 2) secured to the base of the apparatus.

In the FIG. 2 position, sheave 58 is locked in position against clockwise movement in FIG. 3 under the tension of spring 70. When lever 7 is rotated cable 42 rotates sheave 48 anticlockwise in FIG. 3 until screw 60 thereon reaches position 61, at the same time winding the timing mechanism 26 through a gear train 74, 76, 78, 80 and gear 296. Actuation of control 10 then unlocks sheave 58, spring 70 rotating it and sheave 48 under control of the timing mechanism 26, as will be described.

PAPER DRIVE AND INTERLOCK SUBASSEMBLY

Referring to FIG. 2, it will be noted that the paper drive sprocket shaft assembly indicated generally at 14 is rotated through operation of the axis 16, and timing mechanism 26 which are interconnected by gearing. As shown in FIG. 5, assembly 14 comprises a pair of standards 82, 84 secured at their lower ends to the base of the apparatus. The upper ends of the standards support a pair of concentric inner and outer shafts 86 and 88 respectively, one being free to rotate within the other. The inner shaft 86 supports a pair of shutter drive pulleys 90, 92, and is engageable with the outer shaft 88 through a clutch 94 so that when the paper drive is actuated and the clutch 94 engaged, the shutter 6 will be closed. The outer shaft 88 supports a pair of paper drive sprockets 96 and 98 and these sprockets include circumferential teeth 100 adapted to engage the writing paper 4 slightly laterally beyond the window opening 3 and against the underside of the cover 2 of the apparatus so as to draw the paper from the storage roll 30 through the guideways 32 and outwardly through the slot 34 as shown in FIG. 4.

Outer shaft 88 also supports a bead chain sprocket 102 whereby the outer shaft 88 and paper drive sprockets 96 can be rotated by means of the bead chain 20 and paper drive axis 16 as shown in FIG. 2. The bead chain 20 is supported at its other end by a sprocket 104 mounted on the paper drive axis 75

16 which also supports a first gear 22 interconnecting paper drive axis shaft 16 to the interlock axis 18 and a gear 108 interconnecting the axis 16 to one shaft of the timing mechanism, generally indicated at 26 in FIG. 2.

5 Referring to FIGS. 6 and 7, interlock axis 18 is parallel both to the axis of the timing shaft 26 and the paper drive axis 16 and includes a gear 24 in mesh with gear 22 on axis 16 as well as a pair of spaced discs 112 and 114 respectively. Disc 112 has a projection in the form of a pin 116 parallel to the axis 18 and disc 114 is provided with an annular notch 118 as seen clearly in FIG. 7.

A locking gate 120 is pivotally mounted at one end to the base of the apparatus by standard 122 and includes a short reach arm 124 and a long reach arm 126. Arm 126 is bifurcated to provide a slot 128 and the bifurcated end of the arm 126 is supported by a disc 130 pivotally mounted to the base of the apparatus by post 132. Disc 130 has an upwardly projecting pin 134 which pivots gate 120 to locked or unlocked positions by riding in the slot 128. Short reach arm 124 of the locking gate 120 includes an upwardly projecting pin 136 adapted to be engaged by the pin 116 on the disc 112 during rotation thereof in one direction. Approximately intermediate the length of the long arm 126 the latter is provided with an upwardly projecting lug 138 (FIG. 7) adapted to engage the disc 114 at one end of the annular notch 118 and lock the axis 18 against rotation. The pivotal mounting of the locking gate 120 allows it to be moved to the left (locking) and to the right (unlocking) as shown in FIG. 6, the right-hand position 159 being shown in phantom line. Suitably placed stop members 140 and 142 limit the sideways movement of the gate 120.

Pin 134 of the disc 130 is placed under tension of a spring 144 which is connected at one end to the pin 134 and at the other end to a hook 146. It will be appreciated that if the locking gate 120 is moved to the left, the spring 144 will maintain it in that position against the stop 140 and if it is swung over to the right position 159 shown in phantom line, as it passes over center, the spring 144 will also maintain long reach arm 126 against stop member 142.

40 The means for unlocking the locking gate 120 (as well as the paper drive axis 16 geared thereto) consists of an actuating lever 148 placed in the path of crank 38 shown in FIG. 2, lever 148 being pivotally mounted to a bracket 150 secured to the base of the apparatus. Bracket 150 also supports an arm 152 which is interconnected to the pivotal end of the locking gate 120 by a rod 154. It will be understood from FIG. 2 as well as FIGS. 6 and 7 that when the main actuating lever 7 is rotated 180° the crank 38 on the other end of lay shaft 36 will contact the actuating lever 148 to shift it to the phantom position 149 of FIG. 7. This moves arm 152 forwardly so that rod 154 is shifted in the direction of arrow 156 and due to its connection with locking gate 120, it pivots the gate under the influence of spring 144 towards its right-hand phantom position 159 shown in FIG. 6. In doing so, the projecting lug 138 on long reach arm 126 of gate 120 is moved angularly outwardly from disc 114 to unlock axis 18 and paper drive axis 16, now free to be rotated by timing mechanism 126.

55 The paper 4 is advanced approximately two inches after each question period so that it is delivered from the slot 34, bringing the next question into the area of the window. This advance is equal to one revolution of gear 22 and sprocket 104 on axis 16.

60 It will be explained later how energy store 12 rotates axis 16 and sprocket 104 but it is to be understood at this point that under certain circumstances, energy store 12 may rotate axis 16 beyond the required one revolution and that axis 16 is so constructed as to allow the energy store to "run out" and at the same time prevent overrotation of sprocket 104. Gear 108, FIG. 6, is secured on axis 16 and is rotated by gear 301, FIG. 11, of the timing mechanism 26. Gear 22 and sprocket 104, however, are mounted concentrically on a sleeve 17 which is freely rotatable on axis 16 with rotation of axis 16 being transferred to sprocket 104 and gear 22 by a thrust plate 19 under pressure against one end of sleeve 17 from a spring

158. When the locking gate 120 is moved to its unlocked position, pin 136 is moved to position 137. At the end of the time cycle or when the question has been answered, gear 108 and axis 16 will be rotated together with sprocket 104 (advancing the paper) and gear 22, both under pressure from spring 158 and thrust plate 19. At the same time, axis 18 with its discs 112, 114 is rotated by the engagement of gear 24 with gear 22. Therefore, pin 116 on disc 112 makes one revolution (counterclockwise in FIG. 7), striking pin 136 on arm 124 to throw locking gate 120 back to its full line position of FIG. 6. This brings projection 138 back into the path of the notch 118 to prevent further rotation of axis 18 and gear 22 and sprocket 104 on axis 16, the prescribed paper movement being achieved. If tension in the energy store remains, gear 108 and axis 16 continue to rotate as thrust plate 19 slips in rotation against the locked sprocket 104. It will be appreciated that the spring power of energy store 12 overcomes the pressure of thrust spring 158 on axis 16.

SHUTTER AND ASSOCIATED DRIVE MECHANISM

The opening of shutter 6 is initiated through the described depression of control 10 and is automatically closed at the termination of the preselected time cycle by rotation of the paper drive axis 16. Prior to the termination of the time cycle, it can also be closed by axis 16, initiated by control 10.

The shutter mechanism is shown in FIGS. 5 and 8 through 10 and referring firstly to FIG. 8, the shutter 6 comprises a strong membrane in a taut condition held between a pair of parallel guides 161 positioned on the underside of the cover 2 of the apparatus. Obviously, the path of travel of the shutter 6 is relatively short, being approximately equal to the length of the paper advance, just sufficient to extend downwardly to cover the window opening 3 and upwardly to uncover the same. The guides 161 provide paths of travel for a pair of cables 162 connected at one end to pulleys 164 (upper end of FIG. 4) and 166. Pulleys 166 include a torsion spring and drive shaft 168, 170 respectively to provide tension urging the shutter 6 towards the window opening position. Intermediate the pulleys 164 and 166 shown in FIG. 4, the shutter cables pass over the drive pulleys 90, 92 (FIG. 5), these pulleys being secured to the inner sprocket shaft 86 as previously described. The shutter cables 162 are secured to the shutter drive pulleys 90, 92 by set screws 172 and 174 so that when the pulleys 90, 92 are rotated, by their spring 168, they will advance the shutter to a window-opening position. Remaining with FIG. 5, outer shaft 88 is interconnected to inner shaft 86 through the clutch 94 provided on one end of the outer shaft 88 shown on the right-hand side of the drawing. It will be appreciated that in the illustrated engaged position, rotation of the outer shaft 88 through the paper drive axis 16 and its bead sprocket 102, FIG. 6, will rotate clutch face 94b and the engaged clutch face 94a. The latter is connected to the inner shaft 86 by a pin 176 in an elongated slot 178 in the end of the inner shaft 86. Therefore, shutter drive pulley 90 which is formed integral with clutch face 94a will rotate as will shutter drive pulley 92 on the other end of the inner shaft 86, closing the shutter.

After the shutter 6 has been closed, it is maintained in that position by the interlock action of the locking gate 120 of FIG. 6. In other words, as long as the shutter drive pulleys 90 and 92 are in engagement with the outer shaft 88, they cannot rotate reversely to allow the shutter 6 to open. Inasmuch as the bead chain's sprocket 102 and outer shaft 88 carry out rotation in one direction only, means must be provided for releasing the engagement between the inner and outer shafts 86 and 88 to allow the shutter 6 to open under the tension of torsion spring 168. Referring to FIGS. 9 and 10, the shutter 6 can be closed as mentioned earlier by rotation of the paper drive 16 through either termination of the prescribed time cycle or it can be closed as a result of the testee actuating the control 10 prior to the expiration of the prescribed time cycle. This function is carried out through the apparatus shown in FIG. 14.

According to FIGS. 9 and 10 clutch face 94a is provided with a portion 180 having a circumferential groove 182 therein. A clutch throw rod 184 has inwardly projecting lugs 186 riding in the groove 182 and rod 184 is pivotally mounted in a standard 188 as shown. One end of the rod 184 protrudes through the standard 188 and is provided with a bell crank 190 having a first arm 192 interconnected by a rod 194 to the timing mechanism 26 (FIG. 14) and another arm 196 connected by a rod 198 to a sheave release mechanism 200 shown in FIG. 10. It will be appreciated that if the timing mechanism 26 operates on rod 194 it will pull it in the direction of arrow 202, at the same time acting downwardly on arm 196 in the direction of arrow 204 to disengage the clutch 94 by moving clutch face 94a outwardly from engagement with clutch face 94b. Accordingly, disengagement of clutch 94 by rod 202 releases the shutter drive pulleys 90 and 92 from the interlock of outer shaft 88 and the guide pulley 166 and its associated torsion spring 168 will immediately draw the shutter 6 to an open position from the window opening 3.

The sheave release mechanism (FIG. 10) includes a brake 206 pivotally mounted at 201 to a base 203 and positioned under and against a surface of the large energy store sheave 58, being maintained against that surface by a spring 208. Brake 206 is pivotally connected at 205 to the clutch release rod 198 which is secured at its other end to the arm 196 of the bell crank 190. The large energy store sheave 58 has a groove 210 in a portion of its periphery, this groove being in the path of the brake 206. When the testee rotates lever 7, pulling on cable 42, sheave 48 is rotated until its screw 60 moves through slot 62 until it reaches position 61 shown in FIG. 3. Continued rotation then picks up sheave 58 and rotates it one half turn (i.e., until screw 60 makes one full rotation) putting springs 52 and 70 under tension. When sheave 58 reaches its half turn position, brake 206 is jammed into the groove 210 preventing rotation in either direction of both sheaves 48 and 58. This is the "fully wound" position of energy store 12.

When control 10 is depressed to pull rod 194 to open the shutter (FIG. 9), rod 198 is shifted through action of the bell crank 190 to release the brake 206 from the groove 210 allowing the tension of spring 70 to rotate the timing mechanism 26 through gears 74-78, shaft 80 and gear 296.

CONTROL 10

The position of the control 10 relative to the rest of the apparatus is shown in FIG. 4; in plan view in FIG. 2 just to the right of the main actuating lever 7; in its relation to the shutter closing mechanism in FIG. 14; and in self-detail in FIG. 12. This control affects other portions of the apparatus besides the shutter 6, but for the present its description will relate to the shutter opening and closing only.

As shown in FIG. 12, control 10 consists of a plunger 212 having concentric outer and inner members 214 and 216 respectively. Member 216 is secured at 217 to the base of the apparatus and is maintained in concentric relationship with the outer member 214 by an upper sleeve 218 and the fitting construction of a conical portion 220 at the lower end of the outer member 214. The outer member 214 and the plunger 212 are biased to an up position by means of a spring 222 also concentrically positioned between the members 214 and 216. The lower conical portion 220 of outer member 214 acts on a roller 224 of a slide 226 positioned in a slideway 228 mounted on the base of the apparatus.

With attention to FIGS. 14 and 15, the end of the interconnecting rod 194 remote from the clutch 94 is connected to a pivotal reverse bar 230 and in particular to one arm 232 thereof, this being an upstanding arm as shown in FIG. 9. At the opposite end of the bar 230, there is a downwardly depending arm 234 (FIG. 9) and this arm is connected by means of a rod 236 to a main link 238. The main link 238 has three arms 240, 242 and 244 and rod 236 is connected to the arm 240 along with a further rod 246 which connects link 238 with one end of the slide 226 in the slideway 228. It will also be

noted from FIG. 14 that the link 238 is biased to its illustrated position in that Figure by a spring 248 acting on link 238 through an arm 250 of a switchfork assembly generally shown at 252 and a rod 254 interconnecting the arm 250 and the link 238.

It will be understood therefore from FIG. 14 that when a testee depresses the plunger 212, the slides 26 will be moved to the right in FIGS. 14 or 15 by action of the lower conical portion 220 of the plunger on the roller 224 of the slide. This movement is transmitted to the main link 238 and especially the arm 240 thereof which is partially rotated to the right in FIG. 14, also effecting movement of rod 236 and arm 234 of the reverse bar 230. Due to the positioning of arms 234 and 232 of pivotal reverse bar 230, a pull to the left in FIG. 14 is exerted on rod 194, thereby disengaging the clutch 94 in accordance with the description of FIG. 9, immediately releasing the shutter 6 to an opened position over the window opening 3.

MARKING MECHANISM

The marking mechanism forms part of the timing apparatus, the axis of which is generally indicated at 26 in FIG. 2. The function of the marking mechanism is to indicate the actual amount of time taken by a testee for answering a question, whether or not the answer given is within the prescribed time limit. For example, if the question has a set answer period of 60 seconds and the testee answers the question in 38 seconds, then by pressing the control 10 he effects a marking of the writing paper indicating that 38 seconds were actually taken to answer the question.

FIG. 4 indicates in phantom view the position of a marking wheel 256 in operative and inoperative positions. The operative position is upwardly towards the cover of the apparatus. This marking wheel 256 is provided with indicia (not shown) representing seconds, minutes, or whatever the case may be and the wheel 256 can impress the indicia upon the writing paper 4 by way of a marking ribbon 258. Referring to FIGS. 11 and 13, the marking wheel 256 is mounted for rotation on an arm 260 pivoted for the movement indicated in FIG. 4 by its attachment at 262 to a mount 264 on the apparatus base. The arm 260 and its marking wheel 256 are biased to the lower or inoperative position indicated in FIG. 4 by a plunger spring assembly 266.

If the marking wheel 256 is to pivot its indicia upon the writing paper 4 prior to the expiration of time, then this must be carried out in response to the testee depressing the control 10 which effects closing of the paper advance, shutter 6, etc. FIG. 11 shows that the outer terminal end of arm 260 is provided with a tongue 268 which is positioned somewhat over and in the path of a striker mechanism indicated generally at 270 in FIGS. 13 and 14. The actuation of this striker mechanism 270 serves to flip the marking wheel 256 to its operative position of FIG. 4 and to mark or stamp the writing paper 4, the arm with wheel being brought back to the inoperative position by the plunger spring 266. Striker mechanism 270 (FIG. 14) includes a pair of spaced discs 272, joined by an eccentrically positioned shaft 274 which serves as a mount for one end of a tension spring 276, anchored at its other end to the base of the apparatus as shown in FIG. 13. It will be seen from FIG. 14 that one disc 272 includes a striker cam 278 positioned so as to act upon the tongue 268 of the arm 260 while the other disc includes a tongue 280 which is in contact with a tripping gate 282 interconnected to the arm 244 of the main link 238 by a rod 284. See also FIG. 15.

It will be readily understood from FIG. 13 that the tripping gate 282 prevents rotation of the striker mechanism 270 by the tension spring 276. However, it will also be noted that by removing the tripping gate 282, tension spring 276 will immediately swing the striker mechanism 270 around so that the cam 278 will contact the tongue 280 and cause the marking wheel 256 to stamp or mark the paper 4. It will also be apparent from FIG. 14 that this removal of the tripping gate 282

and the resulting stamping operation results from depression of the control 10 and movement thereby of slide 226, connecting rod 246, main link 238 and connecting rod 284. Therefore, the shutter 6 can be closed and the writing paper 4 marked simultaneously by depression of the control 10.

The striker mechanism 270 is mounted on one end of a stub shaft 286 parallel with the power shaft 80 as shown in FIG. 2. The other end of stub shaft 286 supports an integrated clutch and pulley 287, 288, respectively, the clutch being of the uni-directional slip type, slipping clockwise in FIG. 14 in relation to pulley 288. A tension spring 290 interconnects the pulley 288 with a shaft support 271 for rotating the discs 272 to their FIG. 14 position after cam 278 is released. The pulley 288 is interconnected with a pulley 292 on the inner end of power shaft 80 by means of a rope 294 maintained in tension by spring 290. Assume for the moment that the testee completes his answer prior to the expiration of the time period and depresses the control 10. This will pull back the tripping gate 282 whereby the spring 276 will rotate the striker mechanism 270 so that cam 278 contacts tongue 268 to operate the marking wheel 256. As the striker mechanism 270 is released by the tripping gate 282, spring 290 rotates clutch 287 anticlockwise as well as shaft 286 and striker assembly 270 until the tongue 280 again contacts the tripping gate 282. The need for spring 290 will be appreciated from FIG. 13, in that, after a marking sequence, such as that just described, the spring 276 can only rotate the striker mechanism 270 to the extent of approximately 150°.

TIMING MECHANISM

The timing mechanism whose axis is indicated at 26 in FIG. 2 governs the release of spring tension from the energy store 12. After the latter is loaded by the rotation of lever 7, the timing mechanism 26 allows gradual rotation of energy store sheaves 48 and 58 and relaxing of their springs through connection of power shaft 80 and gear train 74-78.

The timing section is basically built on what appears to be, in FIG. 2, a single shaft parallel to power shaft 80, but which in fact is three shafts all in alignment with one another and comprising, as shown in FIG. 11, a clock shaft 298, a drive shaft 300 and a transmission shaft 302 intermediate those shafts 298 and 300. Each end of transmission shaft 302 is provided with clutches as are the juxtaposed ends of the other two shafts. Thus, one end of shaft 302 as seen in FIG. 11 includes one clutch face 304 adapted to mate with a clutch face 306 on the adjacent end of shaft 298. The outer end of transmission shaft 302 includes one clutch face 308 and matching a like clutch face 310 on the adjacent end of drive shaft 300. It will also be noted from FIG. 14 and FIG. 2 that axially slid able transmission shaft 302 is rotated by means of a gear 312 which is in constant mesh with the gear 296 on power shaft 80. It will be realized from FIG. 2 and from FIG. 11 that depending on the position of transmission shaft 302 and its associated clutches, power shaft 80 will direct power from energy store 12 and will either be rotating clock shaft 298 and its associated mechanism or drive shaft 300 which rotates the paper drive 16 to advance the paper and close the shutter 6.

Referring to FIG. 14, transmission shaft 302 is governed directionally by the switchfork and interlock assembly indicated generally at 252. Arm 250 of this assembly has already been described together with its connection to control 10 through the arm and link arrangement terminating with rod 254 connected to arm 250. The assembly 252 includes a main bifurcated switchfork 314 which is approximately at right angles to arm 250, both said arms being pivotally mounted at 316 to block 318 secured to the base of the apparatus. Switchfork 314 has upper and lower arms passing above and below transmission shaft 302 and in particular the gear 312. Switchfork 314 includes an extension 320 having a circumferential groove 322 which receives a pair of guide pins 324 extending inwardly into the groove from bifurcated switchfork 314. Accordingly, movement to the right in FIG. 14 of

switchfork 314 effects shifting to the right of transmission shaft 302 through the action of guide pins 324 in groove 322 of gear 312. As mentioned before, this will disengage clutch faces 304, 306 and effect engagement of clutch faces 308, 310.

The terminal end of switchfork 314 support a locking tongue 326 adapted for reception in a groove 328 of a locking disc 330 mounted on power shaft 80 adjacent the gear 296. Locking tongue 326 is pivotally mounted to switchfork 314 by a pin 332 and is maintained in the position shown in FIG. 14 by a spring 334 biasing the tongue 326 against a stop member 336. If the control 10 is depressed, the connecting rod and link arrangements terminating in rod 254 rotates the switchfork 314 about pivot 316 against the tension of spring 248 temporarily disconnecting clock shaft 298 while the writing paper 4 is marked by the marking wheel 256. In this movement to the right in FIG. 14, locking tongue 326 on the end of switchfork 314 bears against the chamfered surface of the disc 330, the tongue being depressed against the spring 334, lifting its other end off the stop 336. As soon as the control 10 is lifted by its own spring 222 (FIG. 12) spring 248 will bring the switchfork 314 back into the FIG. 14 position and will effect reengagement of clock shaft 298.

Referring to FIG. 11, clock shaft 298 supports pinion gear 338 with an adjacent sprocket 340 interconnected with a further sprocket 342 on marking wheel 256 by way of a bead chain 344. Therefore, rotation of clock shaft 298 and pinion gear 338 effects rotation of the marking wheel 256. A toothed rack 346 is positioned in a guide 348 for slideable action therethrough by the teeth on the pinion gear 338. It will be seen from FIG. 11 and FIG. 2 that rack 346 has the timing indicator 8 adjustably secured to one of its terminal ends. FIG. 11 also indicates that rotation of the pinion gear 338 and movement of rack 346 from 60 seconds to 0 seconds is effected through the energy store 12 and power shaft 80 with its associated gear 296 effecting rotation of clock shaft 298.

A pendulum gear 350 is mounted adjacent the terminal end of clock shaft 298 and is interconnected with the pinion gear 338 by means of a one-way slip clutch assembly 352 (FIG. 2) allowing rack 346 and pinion gear 338 to be moved in one direction independently of the pendulum gear 350.

FIGS. 11 and 17 illustrate an escapement mechanism indicated generally at 354 consisting of a V-shaped pendulum 356 with pair of arms 358, 360, the terminal ends of the arms have inwardly directed dogs 362 and 364 adapted sequentially to engage teeth 366 on the pendulum gear 350.

Pendulum 356 is pivotally mounted at 368 to a mounting plate 370 secured to the base of the apparatus. This mounting plate also carries a pendulum balance 372. It will be noted that the pendulum 356 acting on the gear 350 allows the clock shaft and the associated pinion gear 338 to rotate under the spring tension of the energy store 12 by way of clutches 304, 306 shaft 302, gear 296, power shaft 80 and gear train 74, 76, 78. As the pendulum action releases the gear 350 one tooth at a time, pinion gear 338 simultaneously moves the rack 346 upwardly in FIG. 11 indicating the seconds ticking off on the time indicator and scale 8 and 9. Also, sprocket 340 and bead chain 344 rotate the marking wheel 256 which also includes indicia of the elapsing time.

The time indicator 8 also includes a bumper 374 adjustably secured to the rack 346 by screws 375, the bumper having a sloped contact edge 376. If the testee does not answer the question prior to the elapsed time of one minute, the edge 376 of the bumper will contact a roller 378 on the terminal end of the switchfork arm 250 effecting movement of that arm to an operative position indicated in phantom line at 380. As shown in FIG. 14, this terminates the normal time cycle of one minute and the movement of the switchfork arm 250 effects several operations, namely (a) rotates arm 240 on main link 238 of connecting rod 254, actuating the marking wheel 256 through action of the connecting rod 284, tripping gate 282 and tongue 280 respectively; (b) releases sheave brake 200; and (c) guide pins 324 on switchfork arm 314 disengages

clutch faces 304 and 306 between transmission shaft 302 and clock shaft 298 and effects engagement of the clutch faces 308 and 310 between transmission shaft 302 and drive shaft 300. This transfers all connection between the energy store 12 and the timing mechanism to the paper drive axis 16 resulting in (i) movement of paper 4 to deliver the answered or unanswered question through slot 34; (ii) closing shutter by axis 16 as its clutch 94 is disengaged by rod 236; and (iii) locking axis 18.

10 It will be appreciated that if the time cycle is changed from 1 minute to say 40 seconds then the indicator 8 and bumper 374 can be suitably adjusted upwardly on the rack 346. The bumper 374 will then contact switchfork 314 of the 40 second mock instead of the 1 minute mock.

MARKING RIBBON

It was mentioned in connection with FIG. 4 that the marking ribbon 258 is disposed between the indicia of the marking 20 wheel 256 and the bottom of the writing paper 4 in its guideways 32 so that when the marking wheel 256 is flipped upwardly by the striker mechanism 270 (FIG. 13) the time will be imprinted on the lower portion of the paper. This ribbon must be sequentially moved each time the marking wheel 25 is operated much in the manner of a typewriter operation, thereby providing a good clear ribbon surface for each marking.

FIG. 16 is a plan view of the path followed by the marking ribbon 258 between a storage spool 382 and take up spool 384. The spools 382 and 384 are secured to the base of the apparatus on standards 386 and 388 and it will be appreciated from the position of the spools in FIG. 4 that take up spool 384 is lower in elevation than storage spool 382 due to the sloping design of the cover 2 of the apparatus. Thus the ribbon on storage spool 382, although positioned on the spool normal to the plane of the writing paper 4, is turned 90° by a guide 390 and it is then moved along a ribbon carrier 392 before it is removed therefrom by way of a guide 394 around a roller 396 and onto the takeup spool 384, by this time being again positioned normal to the plane of the paper. Mechanism is provided in association with the spools 382-384 to sequentially advance the ribbon each time the marking wheel 256 is actuated, as follows. A pair of ratchets shown in phantom line at 398 and 400 are secured to the spindles of spools 382 and 384 respectively. The ratchets are actuated upon by a pair of dogs 402, 404 pivotally mounted on a rod 406. The latter is supported by a mount 408 secured to the base of the apparatus and the mount includes an upstanding bar 410. A collar 412 mounted on the shaft 406 adjacent one end thereof provides a stop for a spring 414 biasing the rod 406 in the direction of spool 382, i.e., toward the top of FIG. 16. The movement of the rod 406 in this direction is limited by a second collar 416 also positioned on the rod but on the opposite side of the upstanding bar 410.

The movement of rod 406 in the other direction, i.e., toward the bottom of FIG. 16, is effected by upward movement of marking wheel 256 through apparatus generally indicated at 418. A pair of arms 420 and 422 are secured together via a cross shaft 424 which forms part of the mount 408. Arm 420 is a follower angularly positioned over a protruding shaft 426 on which the marking wheel 256 is mounted. Arm 422 is bifurcated at one end as shown in FIG. 65 16 to partially embrace the shaft 406 intermediate the stop collar 416 and a further collar 428. The interconnection of arms 420 and 422 is such that when the marking wheel 256 is moved upwardly, arm 420 will be moved back, (downwardly in FIG. 16) to effect corresponding directional movement of the bifurcated end of arm 422 against stop 428. This causes movement of rod 406 towards the bottom of FIG. 16 and by the engagement of the ratchet teeth 400 and 398 by the dogs 402, 404, the marking ribbon 258 is moved a minute amount from the storage spool 382 to the take up spool 384. After the marking wheel 256 has been returned to its lowermost posi-

tion shown in FIG. 13 by the spring 266, spring 414 on rod 406 will move the later back to its FIG. 20 position with the stop 416 against the bar 410.

OPERATIONAL SEQUENCE

Although the results of the operation of various subsystems has been described in part throughout this disclosure, a better understanding of the complete workings of the apparatus as a whole will follow a sequential description of the operation.

1. With the apparatus in the FIG. 2 position, a supervisor sets the allotted time for the series of questions (say 60 seconds) by adjusting the indicator 8 and bumper 374 on the rack 346.

2. The testee then rotates lever 7, drawing on cable 42. This action (a) rotates sheave 48 until its screw 60 picks up sheave 58 at the "61" position of FIG. 3 so that sheave 58 is also rotated until its groove 210 is engaged by brake 206. Sheaves 48 and 58 are therefore prevented from reverse rotation by their associated springs 52 and 70, now under tension. (b) simultaneously, gear 74 on sheave 48 rotates meshing gear 76, 78, shaft 80 and gear 296 thereby rotating clock shaft 298, with pinion gear 338 on shaft 298 sending rack 346 to the FIG. 11 or FIG. 2 position as clutch 352 slips. (c) As lever 7 reaches its fully actuated position, crank 38 strikes lever 148 switching gate 120 to the "159" position of FIG. 6 and unlocking the paper drive axis 16.

3. When the testee is ready; he depresses control 10 (a) rotating link 238 to effect disengagement of shutter clutch 94 so that shutter 6 is opened by its spring 168, shaft 86 rotating within outer shaft 88, revealing the question on the writing paper 4. (b) Simultaneously, brake 206 is released from groove 210, starting reverse rotation of firstly sheave 58 under tension of spring 70 with sheave 48 being carried as well. Additionally, gears 74-78 shaft 80, gear 296 and clock shaft 298 all rotate as well but only intermittently under the governing of pendulum 354. Meanwhile, the testee must begin to answer his question as soon as shutter 6 is opened.

4. When the sheave 58 reverse-rotates fully to the expiry of the 60 second limit, either automatically or as a result of the testee finishing earlier, it will also carry back sheave 48 to the "61" position of FIG. 3 where sheave 48 is held by a hook 432 (FIG. 10) engaging a shoulder 350 on sheave 48. Accordingly, as sheave 58 is rotating, rack 346 is being drawn upwardly in FIG. 11 until bumper 374 reaches phantom position 377 to actuate switchfork 314.

5. If the testee should complete his answer before the time limit he presses control 10 to effect the following operations:

a. main link 238 is rotated by rod 246 interconnected to the roller 224;

b. arm 244 of main link 238 pulls tripping gate 232 from tongue 280 and the striker 270 is released, marking wheel 256 imprinting the elapsed time on paper 4;

c. Switchfork 314 is actuated by rod 254 disconnecting clockshaft 298 from power shaft 80 allowing spring 70 to return sheave 58 to the "61" position.

d. Switchfork 314 moves transmission shaft 302 into engagement with drive shaft 300;

e. rods 194 and 236 acting from main link 238 disengage sheave lock 432 from shoulder 350 and disengage shutter clutch 94;

f. tension of spring 52 rotates sheave 48 from "61" position to "60" position of FIG. 3 rotating gears 74-78, shaft 80, gear 296 and drive shaft 300;

g. shaft 300 rotates paper drive axis 16 by gears 301 and 108, rotating as well sprocket 104 to deliver the paper 4 through slot 34 and close the shutter;

h. when the proper amount of paper is delivered, disc pin 116 on axis 18 relocks gate 120 by striking pin 136 on gate arm 124;

i. rotary energy remaining in drive shaft 300 rotates axis 16 within the now locked gear 22 and sprocket 104 through the slipping action of spring 158.

6. If the time period expires without manual operation of control 10, the same simultaneous actions occur with the exception that main link 238 is rotated by the bumper 374 striking the switchfork 314.

The apparatus has now returned to the FIG. 2 position and is ready for the next question.

The embodiments of the invention in which an exclusive property or privilege is claimed are defined as follows:

1. A psychological test taking apparatus comprising, in combination;

- a. a casing having a cover with a writing window in said cover
- b. a supply of writing paper in said apparatus with plural questions printed thereon sequentially and areas for answering each of said questions by a testee;
- c. a shutter for opening and closing said window
- d. paper engaging and drive means for intermittently moving said writing paper across the window so as to expose a question and a respective answering area;
- e. means associated with said shutter for preselecting the maximum length of time for an answer period in which the window remains open;
- f. means operable by the testee for opening said window by moving said shutter to initiate an answer period, operable by the testee only within said maximum preselected length of time for closing said window, further operable means for moving said shutter to voluntarily terminate the respective answer period, and additional operable mean associated with said preselecting means to automatically terminate the respective answer period upon expiration of said maximum preselected length of time;
- g. a timing mechanism associated with said shutter for measuring the actually elapsed time between opening and closing of said shutter, for each answer period;
- h. means associated with said timing mechanism for automatically imprinting the actual duration of the respective answer period onto said paper upon termination of the respective answer period whether voluntarily actuated or automatically controlled;
- i. a source of energy in said apparatus for (i) actuating said paper engaging and drive means; (ii) opening and automatically closing the shutter and (iii) operating said timing mechanism.

2. A test taking apparatus according to claim 1 wherein said shutter comprises guide means positioned on the underside of said casing; a membrane tensioned between said guide means; 50 pulleys and cables retaining said membrane therebetween, said cables running in said guides; a torsion spring connected to said pulleys for urging said shutter to a window opening position; and drive means for closing said shutter.

3. A test taking apparatus according to claim 1 wherein said paper engaging and drive means comprises a drive shaft disposed normal to the path of travel of said paper; sprockets on the drive shaft for engaging said paper and a clutch interconnecting said paper drive shaft with the shutter operating means thereby to advance said paper when the shutter is closed.

4. A test taking apparatus according to claim 1 wherein the source of energy comprises spring means; a crank handle for loading said spring; a paper drive axis connected to said paper drive means a timing axis geared to said spring means and the paper drive axis; and an escapement mechanism on said timing axis for controlling release of the loading spring means; releasing thereof effecting rotation of the timing axis and the paper drive axis to advance said paper.
